(57) **CLAIM**

The ornamental design for a outdoor enclosure, as shown and described.

DESCRIPTION

FIG. 1 is a front, right and top perspective view of a outdoor enclosure, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising honeycombed projections; and,

FIG. 10 is a partial enlarged view of an area labeled 10 in FIG. 1 comprising a front opening.

The broken lines in the drawings depict portions of the outdoor enclosure that form no part of the claimed design. In addition, the dot-dash broken lines in the drawings illustrate an enlarged portion of the design.
